(57) CLAIM

The ornamental design for a bench, as shown and described.

DESCRIPTION

FIG. 1 is a front perspective view of a bench showing the new design;

FIG. 2 is another front perspective view thereof;

FIG. 3 is another front perspective view thereof;

FIG. 4 is another front perspective view thereof;

FIG. 5 is another front elevation view thereof;

FIG. 6 is another back elevation view thereof;

FIG. 7 is another top plan view thereof;

FIG. 8 is another bottom plan view thereof;

FIG. 9 is another right elevation view thereof; and,

FIG. 10 is another left elevation view thereof.

The broken lines in the drawings are for the purpose of illustrating portions of the bench that form no part of the claimed design.

1 Claim, 5 Drawing Sheets
